UNITED STATES PATENT OFFICE

166,192

CHAIR

Bertis F. Hamilton, Columbus, Ind.

Application November 27, 1950, Serial No. 13,141

Term of patent 14 years

(Cl. D15—1)

To all whom it may concern:

Be it known that I, Bertis F. Hamilton, a citizen of the United States, residing at Columbus, Bartholomew County, Indiana, have invented a new, original, and ornamental Design for a Chair, of which the following is a specification, reference being had to the accompanying drawings, forming part thereof.

Fig. 1 is a front elevation, Fig. 2 a top plan view, and Fig. 3 a side elevation of a chair embodying my new design.

I claim:

The ornamental design for a chair, as shown.
BERTIS F. HAMILTON.
